UNITED STATES PATENT OFFICE

MILLER REESE HUTCHISON, OF WEST ORANGE, NEW JERSEY, ASSIGNOR, BY MESNE ASSIGNMENTS, TO ACOUSTIC PRODUCTS COMPANY, OF NEW YORK, N. Y., A CORPORATION OF DELAWARE

TRUNCATED HORN SPEAKER HAVING PLURALITY OF CHAMBERS

Application filed May 24, 1927. Serial No. 183,811.

This invention relates to sound propagating devices of the type in which a mechanical diaphragm is utilized for imparting vibrations to a fluid medium.

5 A diaphragm of a sound reproducing device such as a telephone receiver or a so-called loud speaker, acts as a piston for producing compressions and rarefactions of a column of air enclosed within the horn or 10 within the receiver. The action of the diaphragm is opposed by the friction and inertia of the diaphragm itself and by the pressure of the air column. The horn may correspond to an open end pipe which has

15 the characteristic of being resonant to an air wave having a length double that of the pipe. If the diaphragm vibrates at this resonant frequency of the horn, the vibrations thereof will be in phase with the vibrations 20 which are set up in the air column, and, consequently, less resistance will be exerted upon the diaphragm than will be the case if the vibrations in that element and the air column were not in synchronism.

25 This invention provides a sound propagating device having a new and efficient diaphragm for imparting vibrations to an air column, and in which the friction of the air column is reduced to a minimum. The reflection of the propagated waves back onto the diaphragm is largely prevented by the provision of an air space of constantly increasing cross section from the diaphragm to the open end of the receiver or horn.

35 The above desirable features are accomplished in the present invention by producing waves comprising rarefactions and compressions in a disk-shaped air space, the thickness of which increases from the center 40 toward the periphery. At the center where the movement of the diaphragm is greatest the highest pressure is exerted and as the wave which is produced travels outwardly in concentric circles the cross section of the air

45 space constantly increases. At the outer periphery of the disk the waves may be deflected at right angles and applied to an annular air column of constantly increasing cross section forming a horn. The invention 50 provides for the continuous progression of

the produced waves from the center of the diaphragm to the outward extremity of the horn and thereby largely prevents the reflection against the diaphragm as well as eliminating all inert air space which would produce a damping effect upon the diaphragm. The outer annular air space may be divided into a plurality of columns of different lengths, each of the columns being resonant to a wave of different frequency, such as a note of the chromatic scale. With such an arrangement the various notes of the chromatic scale may be reproduced.

The invention also consists in certain new and original features of construction and combinations of parts hereinafter set forth and claimed.

Although the novel features which are believed to be characteristic of this invention will be specifically pointed out in the claims appended hereto, the invention itself, as to its objects and advantages, the mode of its operation and the manner of its organization, may be better understood by referring to the following description taken in connection with the accompanying drawing forming a part thereof, in which like reference characters have been used to denote like parts in the various figures. Since such illustration is, however, primarily for purposes of disclosure, it will be understood that the structure and the method of operation thereof may be modified in various respects without departing from the broad spirit and scope of the invention.

One embodiment of the invention has been shown for purposes of illustration in the accompanying drawing, in which

Fig. 1 is a front elevation of a sound propagating device constructed in accordance with this invention;

Fig. 2 is a section taken on the line 2—2 of Fig. 1;

Fig. 3 is an end elevation of the device provided with resonating sections of different lengths;

Fig. 4 is a section taken on the line 4—4 of Fig. 3;

Fig. 5 is an elevation partly broken away

showing the invention applied to a multi-horn pancake type loud speaker; and

Fig. 6 is a section on the line 6—6 of Fig. 5.

5 In the following description and in the claims the various parts of the apparatus and details of the invention will be identified by specific names for convenience, but they are intended to be as generic in their 10 application as the art will permit.

10 Referring to the figures more in detail, and in particular to Figs. 1 and 2, a cup shaped diaphragm 1 is peripherally mounted on casing 3, and is actuated by an 15 electromagnetic unit 2, which may be of any desired type, such as for example, the well known push-pull type, in which a force is continuously applied to the armature during movement in both directions. The movable armature may be rigidly connected to 20 diaphragm 1, by connecting link 4 for the purpose of imparting vibrations thereto. Disk 5 having a slightly cone shaped cross section is located parallel to and slightly spaced from diaphragm 1 and provides in 25 connection with said diaphragm, a disk-like air space of cross section increasing toward the periphery thereof, and of minimum cross section at the point at which the vibrations of diaphragm 1 are of greatest 30 amplitude.

35 Diaphragm 1 may be extended to form a slightly tapered cylindrical member 7 terminating in a bell 10. The edges of disk 5 may also be extended to form a tapered cylindrical member 8 which is flared oppositely to member 7, and provides in connection therewith an annular air space of continuously increasing cross section. Cylinder 40 8 may be provided with a bell 9 similar in shape to bell 10 which is formed upon member 7, said bells forming the opening of the annular air space through which waves are to be propagated. Supporting members 45 11 may be employed for rigidly holding members 7 and 8 in spaced relationship.

50 In considering the operation of Fig. 1, when the diaphragm 1 is forced toward disk 5, the air or other gaseous medium therebetween will be compressed, the greatest compression occurring at the center of the diaphragm, at which point link 4 is attached, and at which point the thickness of 55 the disk of air between the diaphragm and disk 5 is the least. The compression thereby introduced into the air disk will be propagated outwardly in circles of progressively increasing diameter until the edge of 60 the disk and the cup-shaped diaphragm is reached. At this point the concentric circles will be deflected in a direction substantially at right angles and will be propagated out through the horn shaped annular space 65 between cylinders 7 and 8. Said cylinders

should be so shaped that the cross section of the annular air space will increase by an amount such that the friction of said cylinders on the moving air column will be reduced to a minimum. Furthermore, the opening between bells 9 and 10 should be 70 such that waves may be transferred to the surrounding atmosphere most efficiently.

75 Referring to Figs. 3 and 4, the various elements described in connection with Fig. 1 are represented by similar reference numerals, and consequently will not be described in detail. In Figs. 3 and 4, however, members 7 and 8 have been shown as extended at a considerable angle to a line normal to the diaphragm, member 8 in effect being cone shaped and terminating in an apex 14.

80 The annular space between said members 7 and 8 has been divided longitudinally by fins 12 in the manner shown in Fig. 3 whereby a plurality of separate air columns are produced through which the air waves are independently propagated. The entire assembly has been shown as truncated, the end thereof terminating in a line 13. This arrangement allows each of the air columns to be of a different length whereby they may resonate at different frequencies. Obviously, the line 13 may take any desired form 85 for imparting the required characteristics to the various air columns. It has been shown as a straight line by way of illustration only. In order to accurately reproduce musical notes, the annular air space may be divided into 12 columns and the length of each column may be such that it will resonate to a 90 particular note of the chromatic scale. As shown in Fig. 3 24 columns may be employed and arranged so that two columns resonate to each of the notes of the scale.

95 In the operation of a device constructed as above, a sound wave, after being reflected from the cup shaped periphery of the diaphragm 1, will be impressed upon each of the various air columns into which the annular space between members 7 and 8 have 100 been divided. The wave will, however, impart the greatest vibrations to the air column which is resonant to the frequency of the wave, and will be re-enforced by said air column and propagated into the surrounding space thereby. The vibrations of frequencies other than those present in the chromatic scale will not find a resonant air column and consequently will not be amplified. The invention, therefore, provides not only for the 105 selective amplification of the various musical notes but effectively suppresses notes of other frequencies, such as for example, those produced by static.

110 In the modification shown in Figs. 5 and 6, the invention is shown as applied to a pancake type speaker in which the air column between disks 20 and 21 is divided by a 115 plurality of spirally extending members 22 120

into various spiral air columns of different lengths and resonant to different frequencies. The diaphragm 1 and the disk 5 co-operating therewith, together with the various actuating elements are similar to those disclosed in Fig. 1 and are given similar reference numerals.

In the operation of this device, the air waves after increasing in diameter until the periphery of diaphragm 1 is reached are reflected into the various spiral air columns through which they are impressed upon the surrounding medium. Each air column then selects and amplifies the wave to which it resonates.

By the present invention, a sound propagating device is produced in which the reflection in the various air columns and the friction in the diaphragm is materially reduced. The diaphragm is allowed to act as piston for producing rarefactions and compressions on the medium acted upon, such as air, but the force required to move the diaphragm is reduced to a minimum by reason of the continuously increasing cross section of the air column in which the vibrations are set up. By providing a plurality of air columns, each resonating at a frequency corresponding to a note in the chromatic scale, the accurate reproduction of musical notes is assured with a consequent elimination of undesired notes of lower frequencies, or of frequencies which are not multiples of one of the notes of said scale.

A reproducing unit constructed in accordance herewith is capable of accurately reproducing all musical notes and of preserving the tonal qualities thereof but serves to suppress all notes of other frequencies. The reproduction is especially efficient by reason of the reduced friction throughout the air column.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. A sound propagating device comprising a substantially flat diaphragm and a cone shaped disk spaced therefrom to form a substantially disk shaped space having a greater cross section at the periphery thereof than at the center.

2. A sound reproducing device comprising a diaphragm, means for imparting vibrations thereto, a member co-operating with said diaphragm to form in connection therewith a disk like air space of increasing cross section, said diaphragm and said member being extended and flared to produce an annular

space of increasing cross section and a plurality of longitudinally extending members for dividing said annular air space into a plurality of separate air columns, each of said air columns being of a suitable length to resonate to a note corresponding to a particular frequency in the chromatic scale.

3. A sound reproducing device comprising a diaphragm means for imparting vibrations thereto, a member co-operating with said diaphragm to form in connection therewith a disk like air space having a cross section increasing toward the periphery, said diaphragm and said member being extended and flared to produce an annular space of increasing cross section, and a plurality of longitudinally extending members dividing said annular air space into a plurality of separate air columns, each of said air columns being resonant to notes of a definite frequency.

4. A sound reproducing device comprising a diaphragm, means for imparting vibrations thereto, a member co-operating with said diaphragm to form in connection therewith a disk like air space of cross section increasing toward the periphery, said diaphragm and said member being extended at substantially right angles and flared to produce an annular space of increasing cross section, and a plurality of longitudinally extending members for dividing said annular air space into a plurality of separate air columns, each of said air columns being resonant to waves of a different frequency.

5. A sound reproducing device comprising a cup shaped diaphragm peripherally supported, means for vibrating the center portion thereof, a member co-operating with said diaphragm to form in connection therewith a disk like air space of cross section increasing toward the periphery, said diaphragm and said member being extended at substantially right angles and flared to produce an annular space of increasing cross section, a plurality of longitudinally extending members for dividing said annular air space into a plurality of separate air columns, each of said air columns being of a suitable length to resonate to a note having a particular frequency to the chromatic scale.

Signed at New York, in the county of New York and State of New York this 20 day of May, A. D. 1927.

MILLER REESE HUTCHISON.
